(57) **CLAIM**

I claim the ornamental design for a bracelet, as shown and described.

DESCRIPTION

FIG. 1 is a front perspective view of a bracelet showing my new design;

FIG. 2 is a front elevational view, in an unclasped position; and,

FIG. 3 is a rear perspective view, in a clasped position. The broken lines shown in the drawings show environment and form no part of the claimed design.

1 Claim, 3 Drawing Sheets

FIG. 1

FIG. 2

FIG. 3
